UNITED STATES PATENT OFFICE.

ARMAND A. RITTER, OF WEEHAWKEN, NEW JERSEY, ASSIGNOR TO RITTER MANUFACTURING COMPANY, OF RAILROAD, PENNSYLVANIA, A CORPORATION OF DELAWARE.

HOLDER FOR CLEANING UTENSILS.

1,187,391.

Specification of Letters Patent. Patented June 13, 1916.

Application filed October 27, 1915. Serial No. 58,129.

To all whom it may concern:

Be it known that I, ARMAND A. RITTER, a citizen of the United States, residing at Weehawken, county of Hudson, and State 5 of New Jersey, have invented certain new and useful Improvements in Holders for Cleaning Utensils, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

The principal object of the invention is to interchangeably mount cleaning utensils 20 such as mops and brushes of different kinds upon the same handle-stick.

Another object of the invention is to provide, as an article of manufacture, a mop-wringer and support for mops of different 25 kinds.

Other objects will appear in connection with the following description.

Figure 1 of the drawings is a view in perspective, showing my improved mop-wringer and holder for mops and brushes 30 with a scrubbing-brush detachably mounted thereupon. Fig. 2 is a view in perspective of the scrubbing-brush and its supporting frame detached from the handle-stick. Fig. 35 3 is a similar view of a mop or brush formed of strands of cord, and the frame upon which the same is supported, the device shown in Fig. 3 being interchangeable with that shown in Fig. 2, upon the handle-stick 40 shown in Fig. 1. Fig. 4 is a view in perspective of the cross-bar-frame detached from the handle-stick. Fig. 5 is a view in side elevation showing the handle-stick and the parts permanently mounted thereon used 45 as a support and wringer for a mop-cloth.

Referring to the drawings wherein the invention is shown in preferred form, 1 is the handle-stick having secured upon one of its ends a cross-bar-frame formed of a 50 single piece of wire bent at its middle to form a loop, 2, adapted to embrace the stick, the frame being of general triangular form having cross-bars, 3, extending in opposite directions from the loop, 2 and the handle-stick, and brace-rods, 4, extending from the

outer ends of the cross-bars, 3, diagonally to the handle-stick to which their ends are secured by a bolt or rivet 5.

As shown in Figs. 1 and 2, a scrubbing-brush, 6, is mounted upon a supporting 60 frame made of a single piece of wire bent at its middle to form a loop-portion, 7, adapted to engage a laterally projecting-stud, 8, on the handle-stick and having its 65 ends bent to form hooks, 9—9, engageable with the respective cross-bars, 3—3. Intermediate portions, 10—10 of this wire-frame pass through the back of the brush, 6, and 70 form supports for the brush; and these brush-supporting portions or members are 70 in a plane at substantially right angles to the plane of the loop-portion 7. The distance between the loop-end of the loop-portion, 7, and the hooks, 9—9, is somewhat 75 less than the distance between the stud, 8, and the cross-bars, 3—3, but the resiliency of the wire-frame is such as to permit the loop-portion, 7, after the hooks, 9—9, have been engaged with the cross-bars, 3—3, to be sprung over the stud, 8, to the position 80 shown in Fig. 1, in which position the brush is detachably, though securely mounted upon the handle-stick.

The form and texture of the brush may be 85 varied as desired.

In Fig. 3, I have shown a brush-supporting wire-frame having a loop-portion, 7^a, adapted to engage the stud, 8, and hook-portions, 9^a—9^a, adapted to engage the cross-bars 3—3, and intermediate portions at right 90 angles to the loop-portion, 7^a, upon which is mounted a brush, 6^a, made of strands of cord or rope forming a floor-brush or mop, such as is used for applying oil to floors. The frame and brush or mop thus formed 95 are mounted upon the handle-stick in the same manner as the device shown in Fig. 2, by engaging the hooks, 9^a—9^a, with the respective cross-bars, 3—3, and springing the loop-portion, 7^a, over the stud 8. 100

To adapt the handle-stick for use as a wringer and holder for a wet mop, I provide the handle-stick near its end with oppositely projecting-studs, 21—21, with which one end of a mop-cloth, 11, can be detachably connected by means of cord, 12, the other end of the mop-cloth being engageable with a double hook, 13, on the lower end of a crank-shaft, 14, which is rotatively mounted in a bearing, 15, obliquely to the 110

handle-stick 1. The bearing, 15, is preferably formed of a wire-coil having its ends, 16 and 17, extending through the handle-stick, the end, 17, projecting out from the stick sufficiently to form a support for laterally projecting-handle 18. The crank-shaft, 14, has on its upper end a crank-handle, 19, whereby the shaft can be rotated. A coil of wire, 20, incloses the lower end of the crank-shaft, 14, between the hook, 13, and the bearing, 15, and serves as a washer to prevent the shaft, 14, from being pulled so far upward that the hook, 13, engages the handle-stick 1. In using the wet mop, 15 the surplus water is wrung out of the cloth by rotating the crank-shaft, 14, to cause the mop-cloth to be tightly twisted, as shown in Fig. 5. After the surplus water is removed, the mop-cloth is untwisted by reversely rotating the crank-shaft until the mop-cloth forms a simple loop, as indicated by dotted lines 11^a, in Fig. 5.

What I claim as new and desire to secure by Letters Patent is—

25 1. In a holder for a cleaning utensil, the combination with a handle having oppositely projecting cross-bars, and a laterally projecting stud; of a frame of resilient material having cleaning utensil supporting rods terminating in hooks engageable with the respective cross-bars and a stud-engaging member forming an angle with said rods.

2. In a holder for a brush cleaning uten-

sil, the combination with a handle having 35 oppositely projecting cross-bars, and a laterally projecting stud; of a frame formed of a single piece of wire bent at its middle to form a loop-portion engageable with said stud and having its ends bent to form 40 hooks engageable with said cross-bars and having intermediate portions bent divergently from said loop-portion forming cleaning utensil supporting members.

3. In a holder for a brush cleaning utensil, the combination with a handle having a laterally projecting stud; of a head formed of a single piece of wire with its middle portion secured in engagement with the end of the handle and bent to the general form of a triangle forming oppositely projecting cross-bars and diagonal braces extending from the ends of the cross-bars to the handle and secured thereto; and a frame formed of a single piece of wire bent 55 at its middle to form a loop-portion engageable with said stud and having its ends bent to form hooks engageable with said cross-bars and having intermediate portions bent divergently from said loop-portion forming cleaning utensil supporting members.

In testimony whereof, I have hereunto set my hand this 19th day of October, 1915.

ARMAND A. RITTER.
